PROCESS OF ENHANCED SOLVENCY
INDUCTIONJacquelin E. Harvey, Jr., Atlanta, Ga., assignor
of one-half to Southern Wood Preserving Com-
pany, East Point, Ga., a corporation of Georgia

Application March 14, 1941, Serial No. 383,465

5 Claims. (Cl. 196—53)

This invention relates to the enhanced production of solvents.

More specifically, the present invention relates to the enhanced induction of solvency in tars of aromatic content and fractions thereof, including pitches and stripped tars.

This application is a continuation in part of my application Sr. No. 352,654, filed August 14, 1940, for Process of enhanced solvency induction, copending herewith, as to all matter common to the two applications.

An object of the present invention is the enhanced induction of solvency in tars of aromatic content and fractions thereof by the step-wise action of hydrogen, as more fully explained in the following.

A further object of the invention is the enhanced induction of solvency by catalytic means with added provision of maintaining catalysis of optimum conditions.

Further objects of the present invention will become apparent from the following disclosures.

Starting materials of the present process are tars of aromatic content derived from coal, wood, petroleum, gas and/or gases and fractions thereof derived therefrom. Especially attractive as a starting material is tar or fractions derived from coal, as for instance coke oven tar, gas house tar, or low temperature tar. These tars derived from coal, and more especially coke oven tar, are characterized by the presence of high molecular complexes that are so susceptible to thermal degradation that the solvents of the present invention cannot be provided by a single action of hydrogen but must be produced in step-wise manner as hereinafter described. According to the process of the present invention it is further possible, by recycling operations, to convert substantially the entirety of the starting materials remaining liquid into solvents of enhanced value.

It has been found that the induction of solvency, as hereinafter described, is maintained at optimum rate when catalyzed by a sulfide catalyst, provided that said catalyst be maintained at least to a degree substantially in sulphide form. An important part of the present invention consists of maintaining at least a portion of a sulphide catalyst in sulfide form whereby to enhance production of solvents as compared to production of solvents that flow from a catalyzed reaction wherein the entirety or part of the sulfide catalyst is changed to another form.

The following examples will serve to illustrate the general principle upon which the practice of the present invention is based, as well as the process of the present invention.

The invention will be understood from the following description of illustrative steps comprising various methods of securing the objects of the invention, when read in connection with

the accompanying drawing wherein the figure is a diagrammatic sketch of an apparatus for carrying out a form of the process of the invention and wherein the nature of the step carried out in each chamber and the contents thereof are indicated by legend.

Example 1.—A high residue creosote having substantially 48% boiling at 355° C. and substantially 2% coke residue is charged to a high pressure autoclave with addition of one half of one percent sulphur based on creosote, and subjected to the action of hydrogen at 200 atmospheres pressure and a temperature of 400° C.; catalyst molybdenum sulfide; time of reaction, one hour. At the end of the hour period the beneficiated creosote is withdrawn from the autoclave and will be found to have reduced coke residue, specific gravity and viscosity. The beneficiated material is then distilled to an upper limit of 250° C. to provide the distillate as an intermediate starting material. The intermediate starting material is then subjected, in the autoclave to the further action of hydrogen wherein temperature is 475° C. and the pressure 200 atmospheres; catalyst, molybdenum and chromium sulfide; one eighth of one percent sulphur is added to the intermediate starting material prior to being charged to the autoclave. Processing of the intermediate starting material is continued until sample withdrawn show that there has been induced an increment of low boiling fractions in excess of fractional increment in the high boiling range and the beneficiated material has a solvency in excess of its intermediate parent material.

The catalysts aforesigned were repeatedly used in recurring cycles of hydrogen action and maintained substantially their initial activity other than decrease expected through normal aging.

Some starting materials may contain sufficient sulphur to maintain the catalyst in substantial sulfide form, while others require the addition of sulphur thereto. It is difficult to define the sulphur content necessary, inasmuch as the starting materials vary in sulphur content. As a general rule it can be said that the maintenance of a hydrogen sulfide partial pressure of in the order of one atmosphere will suffice for maintaining the sulfide catalyst in substantial sulfide form, however, the hydrogen sulfide partial pressure in some cases will be satisfactory when maintained at a fractional atmosphere. Partial pressures of hydrogen sulfide of in excess of one atmosphere are usable. In the case of deficiency of sulphur or sulphur bearing material in the starting material whereby to generate hydrogen sulfide for catalyst activity maintenance, sulphur in any form capable of generating hydrogen sulfide may be added to the starting material.

Viewed broadly, the present invention provides

the step of including a partial pressure of hydrogen sulfide of at least a fractional atmosphere whereby to enhance step-wise provision of solvency induction when the present process is practiced in step-wise manner.

It is desirable at times but not entirely essential that the hydrogen sulfide atmosphere be maintained in both cycles of hydrogen action, inasmuch as enhanced reaction flows from the maintenance of said hydrogen sulfide atmosphere in only the first cycle.

Example 2.—A coal tar, specific gravity 1.1641, coke residue in excess of 8% and boiling predominantly above 190° C. is passed through a high pressure reaction vessel while simultaneously flowing hydrogen and hydrogen sulfide therewith at a temperature of 410° C. and 350 atmospheres pressure; hydrogen sulfide partial pressure one atmosphere; catalyst tin sulfide; time of reaction, 75 minutes and the flow of hydrogen 12,000 cubic feet per barrel feed. The beneficiated tar is distilled to an upper limit of 260° C. to provide the distillate as an intermediate starting material. The intermediate starting material is then passed through a high pressure reaction vessel while simultaneously flowing hydrogen therewith; catalyst molybdenum sulfide; flow of hydrogen 6,000 cubic feet per barrel of feed stock; time of contact 2 minutes. The beneficiated material will be found to have a solvency in excess of its intermediate starting material and will be characterized by increment of low boiling fractions in excess of fractional increment in the high boiling range.

Example 3.—A tar fraction of aromatic content, initial boiling point substantially 220° C. and having substantially 50% residue above 355° C. is subjected to the action of hydrogen while contacting a cobalt sulfide catalyst. Temperature is maintained at 410° C. and a pressure at 400 atmospheres; time of contact, one hour; hydrogen sulfide partial pressure one and one-half atmospheres. The beneficiated material will be found to have a lowered coke residue, specific gravity, and viscosity, and condensation of boiling points toward the lower end. The beneficiated material is distilled to an upper limit of 320° C. with the distillate serving as the intermediate starting material. The intermediate starting material is subjected to the action of hydrogen and hydrogen sulfide while contacting a sulfide catalyst at a temperature of 465° C. and a pressure of 200 atmospheres; hydrogen sulfide partial pressure three-fourths of one atmosphere. The finally beneficiated material will be found to have a solvency in excess of its intermediate starting material and will be further characterized by an increment of low boiling fractions in excess of fractional increment in the higher boiling range.

Example 4.—A coal tar pitch specific gravity 1.23 and 15% boiling at 355° C. is passed through a reaction vessel at 390° C. and 200 atmospheres pressure; catalyst vanadium sulfide; the time of contact is one and one-half hours; hydrogen sulfide partial pressure two atmospheres. The beneficiated pitch is again subjected to an identical cycle of hydrogenation. The twice beneficiated pitch is distilled to an upper limit of 210° C. to provide a distillate as an intermediate starting material for solvents of the present invention. The distillate is then subjected to the action of hydrogen at 535° C. and a pressure of 200 atmospheres. The beneficiated distillate will be found to have a solvency in excess of its in-

termediate parent material and will be further characterized by an increment of low boiling fractions in excess of fractional increment in the higher boiling range.

5 In the step-wise action of hydrogen in the present invention, the first action of hydrogen on the starting material is characterized by reduction of coke residue, specific gravity, and viscosity in the starting material. In the first cycle of hydrogen action pressure as low as 50 atmospheres are usable as are temperatures as low as 200° C., however, higher temperatures and pressures are preferred, as for instance temperatures of 350-450° C. or thereabove and pressure of in excess of 200 atmospheres. Pressures and temperatures are, however, not restricted to any definite limitations inasmuch as hydrogen treatment that reduces the coke residue, specific gravity and viscosity of the starting material will proceed at lowered temperatures and pressures. 10 The desired temperatures and pressures are those that will reduce coke residue, specific gravity, and viscosity in a commercial manner. When using continuous operation in the first hydrogen cycle, flows of 10,000-15,000 cubic feet per barrel feed stock have proven satisfactory, however, higher and lower gas flows have proven effective.

15 In the last cycle of hydrogen action, as comprising a part of the present invention, for a given coordination of temperature and pressure as compared to the first cycle, the hydrogen flow in the last cycle is less than the flow in the first cycle. In the last cycle of hydrogen action pressures as low as 50 atmospheres are usable as are temperatures as low as 250° C. however, more elevated pressures and temperatures are preferred, as for instance, pressures of in the order of 200 atmospheres and temperatures chosen from the range between 300-750° C.

20 Aromatic tars of petroleum derivation or as produced from gas or gases serve as suitable starting materials. Tars or fractions thereof, at least once refined by hydrogen or other means also serve as starting materials.

25 *Example 5.*—It has been discovered that when subjecting certain mixtures of refined coal tar fractions to the action of hydrogen in accordance with the present process for the production of solvents and/or plasticizers that the formerly accepted teaching that product increment, depolymerization and/or hydrogen absorption are linear functions of the time, is not followed.

30 When subjecting a mixture of crude coal tar fractions boiling predominantly above 250° C. or 275° C. to the action of hydrogen, research has disclosed that the newly induced products, depolymerization and/or hydrogen absorption are linear functions of the time. As an example, when the above mixture of crude coal tar fractions is subjected to the action of hydrogen for 2-, 5-, and 8-hour periods, the newly induced products, depolymerization and/or hydrogen absorption were linear functions of the time element.

35 One of the preferred starting materials of the present process is a mixture of refined coal tar fractions boiling predominantly above 355 or 380° C. Such a starting material is conveniently the final residue resulting from evaporating coal tar to dryness or substantial dryness and then stripping wood preservative from the distillate. This final residue mass of refined coal tar fractions is an especially suitable refined coal tar pitch to be used as starting material of the 40 present process. However, in contradistinction

to the mixture of crude coal tar fractions boiling predominantly above 250 or 300° C., when the aforesigned preferred starting material is subjected to the action of hydrogen for production of solvents and/or plasticizers, the newly induced fractions, depolymerization and/or hydrogen absorption are not, as described for the other crude mixture of tar fractions, linear functions of the time. A critical period of treatment by or with hydrogen exists, and which if exceeded causes loss of newly induced fractions, polymerization and/or lessened hydrogen absorption on certain fractions of the preferred starting material under treatment.

The critical time element because of the obvious possible variations in the characteristics of the aforesigned refined coal tar pitch cannot be spoken of as an arbitrary figure. It can be stated, however, that if the refined coal tar pitch were to be subjected to the action of hydrogen for such a length of time, which for other crude tar fractions would illustrate that the newly induced fractions, depolymerization and/or hydrogen absorption were linear functions of the time element, loss of induced products, polymerization and/or lessening of hydrogen absorption would occur. When treating the refined coal tar pitch by or with hydrogen, the critical time element is in the order of about three hours.

In the disclosures made herein and in the appended claims distillate removal of low boiling portions from the beneficiated material is considered the equivalent of fractional removal by gas movement, solvent action or the like. The converse also obtains.

A refined coal tar pitch selected from the group boiling predominantly about, and above, 355° C., characterized by aromatic content, a specific gravity in excess of 1 and a coke residue in excess of in the order of 2 is subjected to the action of hydrogen while contacting a molybdenum sulfide catalyst. The temperature is maintained at 410° C. while maintaining a pressure of 375 atmospheres; time of contact two hours; hydrogen sulfide partial pressure one and one quarter atmospheres. The beneficiated material will be found to have a lowered coke residue, specific gravity and viscosity, and condensation of boiling points toward the lower end. The beneficiated material is distilled to an upper limit of 340° C. with the distillate serving as the intermediate starting material. The intermediate starting material is subjected to the action of hydrogen at a temperature of 535° C. and a pressure of 200 atmospheres. The finally beneficiated material will be found to have a solvency in excess of its intermediate parent material and will be further characterized by an increment of low boiling fraction in excess of fractional increment in the higher boiling range. By the higher boiling range is meant, as an example, the upper half of the boiling range. When subjecting a refined coal tar pitch to the action of hydrogen in accordance with the present process unless the time period of the first hydrogen action is controlled at or below the critical time, there will be experienced loss of fractional increment, polymerization and/or lessening of hydrogen absorption. The critical time element is in the order of about three hours and by the employment of shorter periods, fractional increment, depolymerization and/or hydrogen absorption follow the accepted teaching that they are linear

functions of the time element. By exceeding the critical time element the converse is true.

By the term beneficiated as used herein and in the appended claims is meant the starting or intermediate starting material at least once subjected to the action of hydrogen in accordance to the present process.

All sulfide catalysts effective in the presence of hydrogen are usable, as for instance those of the 6th and 8th periodic groups in any form or shape, as for example supported on carriers and promoted or not; other catalysts are usable therewith.

Other catalysts or materials influencing splitting or decomposition may be used in conjunction with aforesaid sulfide catalysts.

In both cycles of hydrogen action, the present process is predicated on so controlling the reaction conditions that ring structures are not opened with the subsequent formation of liquid chain or paraffin structures to the extent that the solvents of enhanced solvency of the present invention are impossible to manufacture.

In the cyclic action, process conditions are so controlled as to induce no substantial percentage of carbonaceous increment. When utilizing most of the starting materials, the first action of hydrogen is characterized by the depolymerization of high molecular complexes. By the term high molecular complexes is meant those high boiling fractions especially susceptible to thermal degradation.

In the second cycle of hydrogen action periods of as short as one minute at operating conditions have proven beneficial, however, longer or shorter periods may be used as for instance several minutes. As a general rule, it may be said that the time element in said second cycle is that period necessary to provide final increment of low boiling fractions in excess of fractional increment in the higher boiling range, and to induce solvency.

The hydrogen supply used in the present process may come from any convenient source, as for instance by the disassociation of methane. If desired any diluting gas may be used in connection with the hydrogen.

When the starting material has been subjected to the first cycle of hydrogen action that reduces coke residue, specific gravity and viscosity, the stripping of the beneficiated mass may be effected at any point desired as for instance 200° C., or higher, or lower. Generally the point of stripping is determined by the boiling range desired in the product flowing from the final action of hydrogen in the second cycle.

Within the limits of the boiling range of the finally beneficiated material, solvents and/or plasticizers may be fractionated therefrom, as for instance to provide substitutes for the boiling range or ranges of any of the following:

Product:	Boiling Range
Benzol	°C. 78-120
Toluol	°C. 100-150
Hi-flash naphtha	°C. 150-200
High boiling crudes	°C. 150-290
Plasticizers	°C. 160-360

The residue incidental to stripping action, or any residue incidental to solvent or plasticizer recovery from the finally beneficiated intermediate starting material may be recycled for further product production. By such recycling operation the coke residue inherent to the starting

material can be made to substantially finally disappear.

Starting materials include tars and fractions thereof derived from wood, coal, and petroleum including gases of carbon content; as for instance wood tar, pine tar, coke oven tar, gas house tar, water gas tar and synthetic aromatic tars derived from petroleum sources including gases containing carbon.

Starting materials previously subjected to the action of hydrogen are suitable starting materials.

In the disclosures herein made the removing of low boiling fractions by gas movement or pressure release is considered the equivalent of distillation.

When reference is made to high molecular complexes contained in the starting material, and when the starting material contains low boiling fractions that are not considered high molecular complexes, it is of course obvious that the high molecular complexes contained in the starting material are to a certain extent depolymerized by the solvent present.

An especially attractive manner of practicing the present process is to first depolymerize the starting material with a solvent; as an example, but not in a restrictive sense, a refractory solvent. Such use of a solvent may be employed up to volume for volume, or more. After such depolymerization, the solvent and solute are then subjected to process variables as noted in the foregoing. Such a procedure is especially attractive when treating refined pitch.

Starting materials of the present process also include tars of aromatic content from which low boiling fractions have been removed, as for instance tars from which solvent oils have been removed. Viewed broadly, the starting materials of the present process include tars of aromatic content, fractions of said tar more viscous than the starting material due to removal of low boiling fractions from the starting material, high boiling fractions and pitches.

The evaluation of solvent power is conveniently accomplished by finding the well-known aniline point or Kauributanol number. The evaluation of plasticizing properties is conveniently accomplished by recourse to methods suggested in Chapter VI, "the Technology of Solvents" by Dr. Otto Jordon, Mannheim, Germany, translated by Alen D. Whitehead, Chemical Publishing Company of New York, Incorporated, New York, New York.

Minor changes may be made within the scope of the appended claims without departing from the spirit of the invention. In the claims affixed to this specification no selection of any particular modification is intended to the exclusion of other modifications thereof.

I claim:

1. In the production of a solvent from the refined pitch produced by stripping high temperature coal tar to at least about substantial dryness, and fractionating the overhead material to recover a liquid useful as a wood preservative, and a higher boiling fraction boiling predominantly above 355° C., the process which comprises: subjecting said higher boiling fraction to the action of a relatively high flow of hydrogen at a pressure in excess of about 50 atmospheres and a temperature between about 350-450° C. in the presence of hydrogen sulfide whilst contacting a sulfide catalyst for a period not in excess of about three hours, whereby to avoid loss of

newly induced fractions; stripping newly induced fractions from the beneficiated material; and subjecting at least a portion of said stripped fractions to the action of a relatively low flow of hydrogen at a pressure of at least about 50 atmospheres and a temperature between 465-535° C. to provide an increment of fractions in the lower boiling range in excess of fractional increment in the higher boiling range.

10 2. In the production of a solvent from the refined pitch produced by stripping high temperature coal tar to at least about substantial dryness, and fractionating the overhead material to recover a liquid useful as a wood preservative, and a higher boiling fraction boiling predominantly above 355° C., the process which comprises: subjecting said higher boiling fraction to the action of a relatively high flow of hydrogen in the presence of hydrogen sulfide whilst contacting a sulfide catalyst for a period not in excess of about three hours, whereby to avoid loss of newly induced fractions; stripping newly induced fractions from the beneficiated material; and subjecting at least a portion of said stripped fractions to the action of a relatively low flow of hydrogen to provide an increment of fractions in the lower boiling range in excess of fractional increment in the higher boiling range; and fractionating the last named beneficiated material to segregate a solvent.

15 3. In the production of a solvent from the refined pitch produced by stripping high temperature coal tar to at least about substantial dryness, and fractionating the overhead material to recover a liquid useful as a wood preservative, and a higher boiling fraction boiling predominantly above 355° C., the process which comprises: subjecting said higher boiling fraction to the action of a relatively high flow of hydrogen in the presence of hydrogen sulfide whilst contacting a sulfide catalyst for a period not in excess of about three hours, whereby to avoid loss of newly induced fractions; stripping newly induced fractions from the beneficiated material; and subjecting at least a portion of said stripped fractions to the action of a relatively low flow of hydrogen to provide an increment of fractions in the lower boiling range in excess of fractional increment in the higher boiling range; and fractionating the last named beneficiated material to provide a solvent boiling preponderantly between 100° C. and 150° C.

20 4. In the production of a solvent from the refined pitch produced by stripping high temperature coal tar to at least about substantial dryness, and fractionating the overhead material to recover a liquid useful as a wood preservative, and a higher boiling fraction boiling predominantly above 355° C., the process which comprises: subjecting said higher boiling fraction to the action of a relatively high flow of hydrogen in the presence of hydrogen sulfide whilst contacting a sulfide catalyst at a pressure in excess of about 50 atmospheres and a temperature selected between about 350-450° C. for a period not in excess of about three hours, whereby to avoid polymerization; stripping newly induced fractions from the beneficiated material; and subjecting at least a portion of said stripped fractions to the action of a relatively low flow of hydrogen at a pressure of at least about 50 atmospheres and a temperature between 465-535° C. to provide an increment of fractions in the lower boiling range in excess of fractional

increment in the higher boiling range, to produce a solvent.

5. In the production of a solvent from the refined pitch produced by stripping high temperature coal tar to at least about substantial dryness, and fractionating the overhead material to recover a liquid useful as a wood preservative, and a higher boiling fraction boiling predominantly above 355° C., the process which comprises: subjecting said higher boiling fraction to 10 the action of a relatively high flow of hydrogen in the presence of hydrogen sulfide whilst contacting a sulfide catalyst at a temperature and pressure in excess of about 400° C. and about 50

atmospheres, respectively, for a period not in excess of about three hours, whereby to avoid lowered hydrogen absorption; stripping newly induced fractions from the beneficiated material; and subjecting at least a portion of said stripped fractions to the action of a relatively low flow of hydrogen at a pressure of at least about 50 atmospheres and a temperature between 465-535° C. to provide an increment of fractions in the lower boiling range in excess of fractional increment in the higher boiling range, to produce a solvent.

JACQUELIN E. HARVEY, JR.
